US00D552591S

(12) **United States Design Patent** (10) **Patent No.:** **US D552,591 S**
(45) **Date of Patent:** **** Oct. 9, 2007**

(54) **STORAGE MEDIUM**

(75) Inventor: **Michio Deguchi**, Tokyo (JP)

(73) Assignee: **Sony Corporation**, Tokyo (JP)

(**) Term: **14 Years**

(21) Appl. No.: **29/255,339**

(22) Filed: **Mar. 8, 2006**

(30) **Foreign Application Priority Data**

Sep. 8, 2005 (JP) D2005-026060

(51) **LOC (8) Cl.** **14-01**

(52) **U.S. Cl.** **D14/167**; D14/496

(58) **Field of Classification Search** ..... D14/496, D14/401, 435, 474, 483, 217, 137, 138, 160, D14/168; 345/156, 169, 173-179, 905; 715/727-729, 715/864; 455/11.1, 7, 73, 344-347, 93, 95; 370/342-344; 369/1, 2, 6, 12; 463/43-47; 273/148 B

See application file for complete search history.

(57) **CLAIM**

The ornamental design for a storage medium, as shown and described.

DESCRIPTION

FIG. 1 is a perspective view of a storage medium showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

Portions of the figures that are shown as broken lines are for illustrative purpose only and form no part of the claimed design.

1 Claim, 7 Drawing Sheets
